UNITED STATES PATENT OFFICE

KARL RICHARD LIEBERKNECHT, OF OBERLUNGWITZ, GERMANY, ASSIGNOR TO KARL LIEBERKNECHT G. M. B. H., OF OBERLUNGWITZ, GERMANY

PROCESS FOR MAKING FULL FASHIONED STOCKINGS

Application filed August 22, 1931, Serial No. 558,811, and in Germany October 9, 1930.

This invention relates to a process and machine for knitting full fashioned stockings, and more particularly to the manufacture of both the leg and foot of such a stocking on a single straight knitting machine. One of the objects of the invention is to provide a more perfect stocking than has heretofore been obtained when knitting the entire stocking on one machine.

10 In the drawing:—

Figure 1 is a side elevation of the knitting instrumentalities and the middle portions of the needle bar and transfer bar of a straight knitting machine embodying the invention, partly in section;

Figure 2 is a diagram of the lower end of the leg of a full fashioned stocking made in accordance with this invention;

Figure 3 is a side elevation of the knitting instrumentalities and the middle portion of the needle bar, illustrating the modified form of the process in which press-off is avoided by retracting the needles of the middle portion slightly.

15 It has heretofore been known to make an entire full fashioned stocking on a single straight knitting machine by knitting the usual heel caps or tabs without pressing off the stitches on the instep needles. To avoid this press-off on the instep needles it has heretofore been suggested by patents such as the U. S. patent to Gebers No. 1,584,811, dated April 21, 1925, that the needle bar be divided in three portions, the middle portion corresponding to the instep, and that this portion of the needle bar be withdrawn from the line of knitting instrumentalities at the beginning of the heel so that a press-off cannot occur. One disadvantage of this

20 arrangement, however, is that there is danger of the fabric becoming punctured and cut by the knocking-over bits or sinkers. In view of this it has been suggested that the needle bar be divided into three portions and that the middle portion thereof be pivotally mounted so that the instep needles can be moved out of the range of the sinkers and knocking-over bits during the knitting of the heel. During the first part of the 25 knitting of the heel, however, the fabric of

the heel caps is not long enough to permit the instep portion of the needle bar to remain clear of the knocking-over bits and sinkers and during part of the knitting cycle it lies between the sinkers and knocking-over bits, with the result that the loops thereon are easily torn or damaged.

According to applicant's invention the disadvantages of the methods described above are all avoided by the process and machine which will now be set forth and which involves the use of both the divided needle bar and a divided presser bar. An example of a patent showing a divided presser bar is the U. S. Patent to Nebel No. 1,033,723, dated July 23, 1912. According to this invention the making of the heel is carried out in two steps. During the first step the press-off of the instep needles is prevented either by leaving the instep needles in the knitting line and using mechanism such as a divided presser bar or by moving the instep needles a very slight distance from the knitting line but not far enough for the stitches to be hurt by the sinkers or knocking-over bits. A part of the heel caps is then knitted in the usual doubled or folded form. After this stage has been carried out for twenty or twenty-five courses the pivoted instep portion of the needle bar is swung away until the courses of the heel caps already knit are straightened out and held so by the instep portion of the needle bar. During the first stage in which the knitted courses are held in doubled or folded form the stitches on the instep needles are not appreciably enlarged and the stitches are not in a position to be damaged by the sinkers or knocking-over bits. When a sufficient number of 20 courses have been knit to permit the swinging away of the instep portion of the needle bar beyond and clear of the range of the knocking-over bits and sinkers, the instep portion is swung away and the remainder 25 of the heel caps knit with the fabric held straight.

Referring to Figures 1 and 2 of the drawing, the sinker head 1 contains the presser bar 2 whose mid-portion is adapted to be 100

retracted to the position 2' so that the instep needles cannot be pressed off during the making of the heel caps. The retraction of the middle portion of the presser bar to the position 2' occurs when the leg has been completed and the needles are on the line A, B, C, D of Figure 2. Thereafter the heel caps A, B, E, F and C, D, G, H are begun and knit in the doubled or folded form with the fold lying between the sinkers 3 and the knocking-over bits 4. After, say, twenty or twenty-five courses have been knit the pivotal mid-portion of the needle bar 5 is swung out to the right of the dotted line 5' carrying the needles beyond the reach of the sinkers 3 and the knocking-over bits 4. Thereafter the knitting of the heel caps is completed, the pivotal middle portion of the needle bar gradually swinging further out until it reaches the position 5''. When the heel caps are completed the pivotal middle section can be moved back to its starting position and the foot can be knit on the instep portion of the heel caps in the usual manner.

In Figure 3 I have shown the preferred embodiment of my invention, namely, the machine in which instead of using a divided presser bar the instep portion 6 of the needle bar is swung a short distance out of the knitting line during the first step of the process, in which position 7 it is clear of the presser bar and yet does not bring its stitches far enough out to be hurt by the sinkers or knocking-over bits. After twenty or twenty-five courses have been knit, as in the previously described embodiment of my invention, the second step of the knitting is carried out in a manner similar to that of the first process, namely, the instep portion of the needle bar is swung out until the needles are beyond the range and clear of the sinkers and knocking-over bits and the fabric is held out in a straight line by the instep needles.

What I claim is:

1. In a process for knitting a full fashioned stocking, the steps of knitting a plurality of courses to constitute part of the heel caps and simultaneously preventing press-off of the stitches on the instep needles, then moving the instep needles out of the knitting line and beyond the range of the sinkers and knocking-over bits and knitting the remainder of the heel caps.

2. In a process for knitting a full fashioned stocking, the steps of knitting a plurality of courses to constitute part of the heel caps and simultaneously preventing press-off of the stitches on the instep needles without removing the instep needles from the knitting line, then moving the instep needles out of the knitting line and beyond the range of the sinkers and knocking-over

bits and knitting the remainder of the heel caps.

3. In a process for knitting a full fashioned stocking, the steps of knitting the leg on a straight line of needles, knitting a plurality of courses to constitute part of the heel caps in direct succession to the leg, while simultaneously preventing press-off on the instep needles by moving the latter beyond the range of the presser bar but not out of the range of the sinkers and knocking-over bits, the fabric thus knit being held in doubled-over form, then pivoting the instep needles out of the knitting line beyond the range of the sinkers and knocking-over bits until the heel cap fabric thus far knit is straightened out, knitting the remainder of the heel caps while maintaining the fabric straightened out and then returning the instep needles to the knitting line to knit the foot.

4. In a process for knitting a full fashioned stocking, the steps of knitting the leg on a straight line of needles, knitting a plurality of courses to constitute part of the heel caps in direct succession to the leg while simultaneously preventing press-off on the instep needles without removal of the instep needles from the knitting line, the fabric thus knit being held in doubled-over form, then pivoting the instep needles out of the knitting line beyond the range of the sinkers and knocking-over bits until the heel cap fabric thus far knit is straightened out, knitting the remainder of the heel caps while maintaining the fabric straightened out and then returning the instep needles to the knitting line to knit the foot.

In testimony whereof I have signed my name to this specification.

KARL RICHARD LIEBERKNECHT.
